UNITED STATES PATENT OFFICE.

CHARLES FRANCIS JENKINS, OF WASHINGTON, DISTRICT OF COLUMBIA, ASSIGNOR
TO RADIO PICTURES CORPORATION, OF WASHINGTON, DISTRICT OF COLUMBIA, A.
CORPORATION.

RADIO-PICTURE-FREQUENCY CHOPPER.

Application filed August 30, 1922. Serial No. 585,818.

To all whom it may concern:

Be it known that I, CHARLES FRANCIS JENKINS, a citizen of the United States, residing at Washington, District of Columbia, have invented certain new and useful Improvements in Radio-Picture-Frequency Choppers, of which the following is a specification.

This invention relates to details of methods employed in the transmission of pictures-by-radio, and has for its object means for impressing a picture frequency upon a radio frequency in an inductive coupled circuit at the sending station.

The invention is diagrammatically illustrated in Fig. 1, accompanying this application, Fig. 2 being a detail of same. A is an illuminated picture; b a prismatic ring; c a lens; d a disc with equi-spaced openings peripherally arranged therein; d' a motor for rotating the discs; and e a light-sensitive cell.

The rotation of the prismatic ring (the subject of Patent 1,385,255), or disc, b, hinges the pencil of light to cause it to cross the picture. The lens images the picture onto the light-sensitive cell. This pencil of light is interrupted by the rotation of the disc d, the result being that the conductivity

of the cell is constantly varied, producing 30 a rapidly fluctuating current in the circuit of which it forms a part. This fluctuating current can be used in inductively coupled circuits of radio apparatus, and this is the principal object to be attained.

The varying light values encountered as the pencil of light sweeps across the picture causes fluctuating current values in the cell circuit, frequencies which applicant and assistants have become accustomed to call 40 "picture frequencies."

This method of obtaining fluctuating current with picture frequencies impressed thereon has been found to be very effective in producing results of high quality both in 45 electrical circuits and in picture frequencies.

What I claim is—

In apparatus of the class described, the combination of a lighted surface, a light sensitive cell, a rotating light chopper therebetween, and a prism between the light chopper and the lighted surface, the prism having a constantly changing angle between its sides, all of the elements being in optical alignment.

In testimony whereof I have affixed my signature.

CHARLES FRANCIS JENKINS.
